Filed Mar. 2, 1962, Ser. No. 69,801

Term of patent 14 years

(Cl. D10—9)

FIG. 1

FIG. 2

FIG. 1 is a perspective view of a hinge having an elongated door leaf showing my new design in a partially open position.

FIG. 2 is a perspective view of a modified form of the hinge shown in FIG. 1.

This application is a continuation-in-part of my earlier filed application Serial No. D. 57,880, filed October 6, 1959, and now abandoned, which application is a continuation-in-part of my earlier application, Serial No. D. 48,056, filed October 10, 1957, and which has matured into Patent D. 187,262 issued February 23, 1960.

I claim:

The ornamental design for a hinge, as shown and described.
